UNITED STATES PATENT OFFICE

155,471

DESIGN FOR A HANDLE

Vytant P. Aleks, Rockford, Ill., assignor to National Lock Company, Rockford, Ill., a corporation of Delaware

Application October 21, 1948, Serial No. 149,231

Term of patent 7 years

(Cl. D10—8)

To all whom it may concern:

Be it known that I, Vytant P. Aleks, a citizen of the United States, residing at Rockford, in the county of Winnebago and State of Illinois, have invented a new, original, and ornamental Design for a Handle, of which the following is a specification, reference being had to the accompanying drawing, forming part thereof.

In the drawing,

Fig. 1 is a front elevation of a handle embodying my new design;

Fig. 2 is a plan view thereof;

Fig. 3 is a view in end elevation taken from a position to the right of Fig. 1; and

Fig. 4 is a sectional view on the line 4—4 of Fig. 1.

I claim:

The ornamental design for a handle, substantially as shown.

VYTANT P. ALEKS.
